UNITED STATES PATENT OFFICE.

JAMES B. FAUCETTE, OF LITTLE ROCK, ARKANSAS.

DIVIDING-ENGINE.

SPECIFICATION forming part of Letters Patent No. 398,504, dated February 26, 1889.

Application filed January 28, 1888. Serial No. 262,231. (No model.)

To all whom it may concern:

Be it known that I, JAMES B. FAUCETTE, a citizen of the United States of America, residing at Little Rock, in the county of Pulaski and State of Arkansas, have invented certain new and useful Improvements in Dividing-Engines, of which the following is a specification, reference being had therein to the accompanying drawings.

10 The object of my invention is to construct a dividing-engine which will accurately mark a circular or segmental plate with tangent-graduations to be used upon engineers' transit, protractors, or other similar instruments, 15 for the measurement of angles, although some of the novel features of my invention may be employed upon engines used to mark degrees upon circles.

The invention consists, essentially, in a radially and reciprocally moving marker and tool-holder carried at one end upon a slide fitted to move tangentially to the arc of movement of the tool-holder and held upon the tangent-line while the graduation is effected.

25 My invention also consists in novel mechanism for connecting the tangent-slide and marker to automatically effect a joint operation of the said slide and marker by a continuous movement of the machine, in novel 30 mechanism for reciprocating the tool-holder and marker and for raising and lowering the same upon the work, and certain novel details of construction for supporting the tool-holder and for adjusting the feed mechanism, 35 which will hereinafter appear.

In the accompanying drawings, Figure 1 is a front elevation of a machine embodying my invention. Fig. 2 is a plan thereof. Fig. 3 is a side elevation of the same. Fig. 4 is an 40 enlarged detail of one end of the feed-shaft and mechanism for intermittently moving the same. Fig. 5 is a section of the feed-shaft, showing the shaft-retaining ratchet and pawl.

The frame of the machine consists, mainly, 45 of a table, A, supported upon legs A' and carrying the bracket-arm A², bolted to the upper side of the table to support the gearing and the tool-holding mechanism, and hangers A³, projecting from the under side of said table 50 for the support of the feed-screw and mechanism connected therewith.

The bracket-arm A² has bearings a a' projecting from its forward and overhanging end, which support a vertical shaft, B, and branch arms a², extending laterally from the 55 lower bearing, a'. These arms have end bearings, a³, which support a horizontal driving-shaft, C, also supported in the upper bearing, a, of the bracket A², and serve to operate both the vertical shaft B and a horizontal 60 screw-shaft, D, supported in the hangers A³ beneath the table.

The upper end of the vertical tool-operating shaft B is received in the under side of the bearing a and passes through the bearing a', and carries a bevel gear-wheel, E, between the said bearings a a', and also carries a collar, b, which rests upon the upper side of the bearing a' and supports the shaft.

The bevel gear-wheel E is driven by a similar wheel, E', upon the driving-shaft C, and the lower portion of the shaft B carries a bevel gear-wheel, F, for operating the tool-holder G. This tool-holder and its radial carrier-arm H are supported from the lower end 70 of the shaft B by suspension-arms H', connected by a sleeve, H², having a vertical socket, h, to fit upon the lower end of the said shaft, and a screw, h', on said socket engages with an annular groove, b', therein, which 75 will thus both support the inner end of the radial carrier-arm H above the table and permit the outer end of said arm to swing in the arc of a circle. The outer end of the arm H reciprocates in and is supported by a block, 80 I', projecting upwardly from a sliding plate, I, fitted in a preferably dovetailed guide slot or groove, i, formed in the top of the table, and is moved within said guide-slot by the screw-threaded pendent arm or nut i² on the 85 horizontal screw-shaft D, located beneath the table.

The sleeve H², connecting the upper end of arms H', forms the bearing for a horizontal shaft, K, to which the bevel-gear F' is secured, 95 and the latter is driven by the gear F upon the vertical shaft B. The shaft K also carries cam-wheels K' K², keyed thereto upon opposite ends. The wheel K' serves to raise and lower the outer end of the tool-holder, 100 and the wheel K² serves to reciprocate the tool-holder G. This tool-holder consists of a

bar suspended beneath the radial carrier-arm H by the lever L², pivoted at g to said arm H and at g² to the inner end of the tool-holder, and is operated by the cam-wheel K² 5 and a spring, k, pressing against said lever L², to reciprocate said tool-holder, and the arm L', pivoted on the pin g, has a bent arm, l, projecting therefrom, that passes beneath the said tool-holder bar to raise it at the proper 10 time from its work. This arm L' is operated upon by the wheel K' and spring k'.

The tool-holder arm is held between guide-plates h upon the under side of the arm H, to steady its movement and hold it accurately in 15 position. The plate or work M to be graduated is passed beneath the carrier-arm H and secured centrally beneath the shaft B, to bring its periphery in proper position to be operated upon by the graduating-tool, and is then 20 secured upon the table by clamps A⁴, and when said plate has a central hole said hole receives the screw-bolt N, that passes through the table and serves as the pivot for the carrier-arm H and its supporting-frame, as said 25 bolt is in the axial line of the vertical shaft B and fits into a socket in the under side of the arm H, and serves to partially support and accurately center the pivot end of said arm.

30 To form an additional central support for the carrier-arm, a bracket, A⁵, is secured to the inner side of the bracket-arm A², and its free end receives the journal h⁴, pendent from the arm H.

35 The screw-shaft D is driven from the shaft C and receives an intermittent rotary motion by means of a crank-arm, C', secured to the end of said shaft, said arm having a crank-pin carrying one end of a cord, O, the other 40 end of which is secured to and wound upon a threaded sleeve, D', fitted to revolve upon the end of the shaft D. Said cord carries also a weight, O', which serves to rotate the said sleeve in one direction, while the rotation of 45 the crank C' operates upon the cord O and causes the rotation of said sleeve in the opposite direction. The sleeve D' carries a ratchet-wheel, D², upon one end, which has in engagement therewith a pawl, d, carried upon 50 an arm, D³, secured to the end of the screw-shaft D, and by the alternate rotation of said sleeve in opposite direction the screw-shaft D receives from it and through the ratchet-wheel and pawl an intermittent rotary motion. The shaft D is prevented from being 55 turned backward by the rotation of the sleeve D' upon it, either by frictional contact with its bearings, or preferably by a ratchet-wheel, P, secured to said shaft and by a pawl, P', pivoted to the hanger A³.

60 The sleeve D' is limited in its rotation or movements by arms D⁴ D⁵, secured thereto, and stops D⁶ D⁷, secured to the table or its hanger, to intercept the movement of said arms 65 at the end of their course.

The arms D⁴ D⁵ have slotted saddle-plates d', Fig. 4, and set-screws d² passing through

said slots and into the sleeve, by means of which the arms may be adjusted upon the sleeve, and the extent of movement of said 70 sleeve may be regulated, a greater or less number of ratchet-teeth being thereby caught or passed over by the operating-pawl at each of its movements.

The sleeve may be caused to make any number of revolutions or fractional part thereof without having the arms D⁴ D⁵ intercepted by the stops D⁶ D⁷ on account of the screw-thread d³ upon the outer surface of the sleeve D', which engages with a blade, D⁸, vertically 80 projecting from a bracket-plate secured to the table A, and thus the sleeve is moved endwise upon the shaft and permits the arms to pass between their stops until the end of the required movement of the sleeve is effected 85 and the distance between each graduation to be made upon the arc accurately determined. The extent of movement of the sleeve D' is also regulated in one direction by adjusting the length of the crank-arm C' in a radial 90 groove, c², in the face of a disk, C³, secured upon the shaft C, to thus vary the throw of the crank and permit the cord to be wound any required number of turns or parts of turns upon the said sleeve to cause its rotation. In operation the tool-carrying arm is driven by the shaft to the full length of its movement (over ninety degrees) and then returned to its normal position by hand, and the nut z² may be split to facilitate its removal and resetting upon the screw D.

The tangent-graduations are by the above-described means marked with great accuracy upon the plate, and by changing the movement of the screw the said graduations may 105 be varied to suit the size of the plate and the number of tangential divisions required. The length of every fourth and fifth or other subdivision of the graduations may be increased by varying the number of spurs upon 110 the cam-wheels on the shaft K, and by varying the length of any one of said spurs to thus increase the movement of the marker. The cutting-tool can be adjusted upon the tool-carrier to suit the radius of any arc by 115 sliding it lengthwise thereon; or a tool-carrier of proper length may be substituted for another. This cutting-tool may have a proper weight to indent the work; but a spring may be used to press thereon to deepen the marks. 120

The front edge of the table is provided with a scale in the present instance indicating two feet divided into twenty-four inches, and each inch can be subdivided into hundredths of an inch to set the machine at the start and 125 verify its operation.

Having now fully described my invention, I claim—

1. In a dividing-engine, the combination of the table or work-holder and a radially-moving tool-carrying arm, with a tangent-plate connected with said arm for marking tangent-graduations upon an arc or plate, substantially as described. 130

2. In a dividing-engine, the combination of the table or work-holder and a radially-moving arm for carrying a reciprocating marking-tool, a tangent-plate connected with said arm, and an operating-screw for moving the tangent-plate and carrying the outer end of the radially-moving arm, substantially as described. 5 and passing into a recess in the lower end of the said carrier, substantially as described. 60
3. In a dividing-engine, the combination of a table or work-holder and a radially-moving arm having its outer end carried by an adjustable tangent-plate, and a reciprocating tool-holder supported upon said arm, substantially as described. 10 10 15 20 25 30 35 40 45 50 55 60 65 70 75 80 85 90 95 100 105 110
4. In a dividing-engine, the combination of a table or work-holder and the radially-moving arm carried by an adjustable tangent-plate, a reciprocating tool-holder supported upon said arm, and cam for connecting and intermittently reciprocating said tool-holder, and gearing for moving said tangent-arm, substantially as described. 15 20 25 30 35 40 45 50 55 60 65 70 75 80 85 90 95 100 105 110
5. In a dividing-engine, the combination of a table or work-holder and the radially-moving arm pivoted above the center of the work-plate, the reciprocating tool-holder, a driving-shaft, K, above said center, and arms K² for reciprocating said tool-holder, substantially as described. 25 30 35 40 45 50 55 60 65 70 75 80 85 90 95 100 105 110
6. In a dividing-engine, the combination of a table or work-holder and the radially-moving carrier-arm pivoted above the center of the work-plate, the reciprocating tool-holder, a driving-shaft, K, and an arm, K', for lifting said tool-holder, substantially as described. 30 35 40 45 50 55 60 65 70 75 80 85 90 95 100 105 110
7. In a dividing-engine, the combination of a table or work-holder and the radially-moving carrier-arm having its pivot above the center of the work-plate, the reciprocating tool-holder, a driving-shaft, K, and levers L¹ L², operated by cams upon the said shaft to respectively reciprocate and raise or lower the said tool-holder, substantially as described. 40 45 50 55 60 65 70 75 80 85 90 95 100 105 110
8. In a dividing-engine, the combination of a table or work-holder and an overhanging bracket, a vertical shaft supported thereon, and a tool-carrying arm and tool-holder suspended from said shaft and to be rotated upon said shaft, and gearing for reciprocating the said tool-holder independently of the movement of the said arm, substantially as described. 45 50 55 60 65 70 75 80 85 90 95 100 105 110
9. In a dividing-engine, the combination of a table or work-holder and an overhanging bracket, a vertical shaft suspended therefrom for operating the tool-holder, a tool-holder arm and carrier suspended from said shaft, and a centering-bolt passing through the table 55 60 65 70 75 80 85 90 95 100 105 110
10. In a dividing-engine, the combination of a table or work-holder and a driving-shaft supported above the table, a radially-moving tool-carrying arm and tangent-plate connected therewith, and a screw-shaft fitted under the tangent-plate and operated by the driving-shaft, substantially as described. 65 70 75 80 85 90 95 100 105 110
11. In a dividing-engine, the combination of a table, the driving-shaft connected with and reciprocating the tool-holder, the radial arm and tangentially-located screw-shaft, a sleeve fitted upon said shaft, and means, as described, for connecting the sleeve and shaft D to operate the same, substantially as described. 70 75 80 85 90 95 100 105 110
12. In a dividing-engine, the combination of a table, a driving-shaft connected with and operating the tool-holder, a radial tool-carrying arm and tangent-screw, a sleeve, a crank-arm upon the driving-shaft, a cord connecting said arm and sleeve, substantially as described, and a weight for returning the sleeve to its normal position upon the shaft, substantially as described. 80 85 90 95 100 105 110
13. In a dividing-engine, the combination of a table, the driving-shaft, a radial tool-carrying arm and tangent-screw, a sleeve, a cord for rotating said sleeve, and an arm adjustably supported upon the shaft to operate the sleeve, substantially as described. 85 90 95 100 105 110
14. In a dividing-engine, the combination of a table, a radial tool-carrying arm, a tangent-screw, a sleeve upon said screw, an arm or arms secured to and projecting from said sleeve, and stops supported upon the frame for arresting the movement of said arms, substantially as described. 90 95 100 105 110
15. In a dividing-engine, the combination of a table, a radial tool-carrying arm, a tangent-screw, a sleeve supported upon said screw, stops supported upon the frame, and an arm or arms adjustably secured upon the sleeve to regulate and limit the movement of the sleeve, substantially as described. 100 105 110
16. In a dividing-engine, the combination of a table, a radial tool-carrying arm, a tangent-screw, a screw-threaded sleeve supported upon the screw-shaft, and a fixed blade engaging with the thread of the sleeve to guide it and cause it to move endwise upon the shaft, substantially as described. 105 110

In testimony whereof I affix my signature in presence of two witnesses.

JAMES B. FAUCETTE.
